(57) **CLAIM**

The ornamental design for a connector, as shown and described.

DESCRIPTION

FIG. 1 is a top, front, right side perspective view of the connector.

FIG. 2 is a right side elevational view of the connector.

FIG. 3 is a left side elevational view of the connector.

FIG. 4 is a top plan view of the connector.

FIG. 5 is a bottom plan view of the connector; and,

FIG. 6 is a front elevational view of the connector with the rear elevational view being a mirror image of the same.
